PUSH AND PULL DOOR HANDLE

Kenneth A. Williams, Cutler, Ohio

Application July 18, 1947, Serial No. 761,772

4 Claims. (Cl. 292—167)

1

The present invention relates to latch operating means for doors such as are used in office buildings, dwellings and the like and has more particular reference to inner and outer lever-type handles wherein the outer handle is pushed toward the door and the inner handle is pulled away from the door in a manner to conveniently release a latch.

It is an object of the invention to provide simple and practical door handle means in which the handles are in the form of L-shaped levers for positive and convenient actuation results.

Another object of the invention is to provide lever-type handles which may be readily grasped for operation with one's hand, wet or greasy; a condition which often makes the ordinary door knob objectionable.

Another object of the invention is to provide push-pull handles which coordinate with the "in" and "out" swinging movement of the door, the outside handle being actuated by a push, whereby to enable one to push the handle in a manner to conveniently unlatch the door, when one's hands are otherwise engaged in holding packages, carrying buckets or so "tied up" as to prevent their use in grasping the handle.

Another object of the invention is to structurally, functionally and otherwise improve upon a mechanism required in satisfactorily obtaining the desired push-pull accomplishments.

Other objects and advantages will become more readily apparent in the following description of the accompanying illustrative drawings.

In the drawings, wherein like numerals are employed to designate like parts throughout the views:

Figure 1 is a fragmentary perspective view showing a portion of a door, the lock mounted in said door, and one of the latch actuating handles or levers;

Figure 2 is a fragmentary view, with parts in elevation, in which the latch control means is amply illustrated;

Figure 3 is a horizontal section on the line 3—3 of Figure 4, looking in the direction of the arrows;

Figure 4 is a view at right angles to Figure 3, the section being on the line 4—4 of Figure 3, also looking in the direction of the arrows.

Referring now to the drawings and particularly to Figure 2 the door, which is conventional, is denoted by the numeral 6 and said door is mortised as usual to accommodate the customary-type key controlled lock 1. It is understood, in this connection, that I am not interested in the features of the lock but only in the latch bolt, 55

2

actuating means and door handle. To this end the horizontally slideable latch bolt is denoted by the numeral 8 and the latch 9 on the outer end is projectable and retractable, as is customary.

5 The inner end of the bolt is provided with an elongated eye 10 having a suitable stabilizing guide 11 to facilitate correct operation of the bolt in the lock housing or casing. A supplemental mortise or recess 12 is provided in the door to accommodate an actuating disk 13, said disk being concentrically pivoted and thus mounted in place as at 14. The disk is provided with arcuate slots 15 and 16. One end of the slot 15 is formed into an abutment 17 which is radial to the axial center of the disk and which constitutes a cam thrust surface. A similar abutment 18 is formed at an opposite end of the arcuate slot 16 and this likewise is radial to the axial center 14 and constitutes a second cam surface. 10 15 20 25

20 The numeral 19 designates a suitably shaped and anchored return spring for the latch bolt. This, as seen in Figure 2, has one end anchored and the other free end engaging beneath a boss 21a on the bell-crank 21. The latter is pivotally 25 30 35 mounted as at 22, and the vertical limb carries a stud 22a which, in turn, is operatively joined with the eye 10. Any suitable spring return means 35 may be employed, obviously, for projecting the latch bolt 8 once it has been retracted by the handle means for door unlatching purposes.

Referring now to Figure 4 the outside door handle is denoted and distinguished by the numeral 23 and the inside door handle by the numeral 24. Mechanically both handles are the same in construction that is L-shaped and the long limb is denoted at 25 and the shorter limb at 26. The latter is pivoted as at 27 between spaced parallel outstanding ears 28 on a facing plate 29 mounted on the door. The handle 23 is provided with a stop 30 which checks the inward swinging movement. Also the handle 24 is provided with a similar check or shoulder 31 which strikes the face plate and limits the outward swinging of said handle. The short limb of the handle 23 is provided with an extension which provides a trip finger 32 and this projects into the slot 16 and coacts with the cam surface or abutment 18. The handle 24, that is the short limb portion thereof, is provided with an extension 33 and this provides a trip which extends into the

slot 16 and coacts with the cam abutment 17. It follows that the handles are so mounted and so arranged in relation to the actuating disk 13 that they rotate the disk in a counterclockwise direction. It is evident too that by thrusting or pushing inwardly on the handle means 23, the trip 32 acts on the cam shoulder 18 and turns the disk 13 in a manner to actuate the link 19, eye 10 and latch bolt 8. This results in a release of the latch nose 9. When the handle means is released the spring means 20 serves to return the latch to projected position. It is obvious too that by pulling the handle 24 in a direction away from the door, a similar result is attained. That is to say, the trip finger 33 then engages the shoulder or cam surface 17, which results in counterclockwise rotation of the disk and actuation of the link and latch means. Needless to say, the latch is disengaged or released by a thrust or push against the handle means 23, this being on the outside or exterior of the door; and, the handle means 24 is operated by a pull in a direction away from the door, this being on the interior of the door. The dotted line showings in Figure 4 will assist in obtaining a full understanding of this operational phase of this invention.

A careful consideration of the foregoing description in conjunction with the invention as illustrated in the drawing will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention, what is claimed as new is:

1. Handle means for opening, closing and unlatching a hinged swingably mounted door wherein said door is provided with a spring returned projectible and retractable latch bolt slidably mounted for operation on said door comprising a lever-type handle adapted to be pivotally mounted for operation on the exterior of the door, the said handle being designed to be pushed bodily toward the door for latch releasing purposes, a second lever-type handle also designed to be pivotally mounted on the interior side of the door, said second handle being adapted to be pulled away from the door for releasing the latch, and means for affording an operating connection between said handles and latch bolt embodying a rotary disk for concentric pivotal mounting on said door, and a link eccentrically connected to said disk and adapted to be connected with said

latch bolt, said disk having independent diametrically opposite eccentrically disposed slots, said handles having trip fingers projecting into their respective coacting slots.

5 2. In a structure of the class described wherein in a door is provided with a mortise-type latch including a projectible and retractable spring returned latch bolt and a supplemental mortise coacting with said latch, a disk concentrically pivoted for rotation in said supplemental mortise, a link connected to the inner end of said latch bolt and eccentrically connected with said disk, an L-shaped handle lever pivotally mounted on the exterior of the door, the short limb of said lever 10 having an extension projecting into said supplemental mortise, the extension having a trip finger, said disk having a cam slot, and said trip finger 15 extending into said slot.

20 3. The structure specified in the claim 2, together with a second lever-type handle pivotally mounted on the opposite side of said door, said handle also being of L-shaped form and with said short limb thereof having an extension projecting into said mortise from an adjacent side, and 25 said disk having a second cam slot, and said last named extension extending into said second named cam slot.

4. Operating means for a swingable door equipped with a mortise-type latch employing a spring projected, a handle retracted latch bolt in a casing comprising a disk adapted to be concentrically mounted on the door in operating relation to the casing, said disk being provided with diametrically opposite cam slots, a link eccentrically connected at one end to said disk and adapted to be connected pivotally at its opposite end to the stated projectible and retractable latch bolt, a pair of substantially L-shaped handles adapted to be pivotally mounted on opposite sides 30 of the door, means for pivotally mounting the handles in operative positions, the short arms of the respective handles being provided with offset trip fingers and said trip fingers being adapted to project into the cam slots provided therefor in 35 said disk.
